UNITED STATES PATENT OFFICE

2,201,915

RAILWAY CAR DOOR CONSTRUCTION AND
SEALFinn Oyen, Dormont, Pa., assignor to Railroad
Research Bureau, a corporation of New
Jersey

Application April 13, 1939, Serial No. 267,673

3 Claims.

(Cl. 20—26)

The present invention relates to railway car doors and more particularly to car doors which move horizontally of the car construction for closing openings in the side walls of such cars.

5 An object of this invention is to provide a door for a railway car comprising a rectangular metallic frame having component members thereof formed, associated and secured together to provide a very strong and very light-weight frame to 10 resist the stress tending to distort or warp the door.

Another object is to deform commercial shapes so as to provide a weather-proof and spark-proof door construction.

15 A further object of the invention relates to forming trough-like channelways at the front edge and top of the door, which channelways are in communication with each other and with the open bottom and rear edge of the door frame.

20 Other objects and advantages will become apparent as the description proceeds, and reference is had to the accompanying drawings, in which:

Figure 1 is an elevation of the car door of the present invention;

25 Figure 2 is a section on line II—II of Figure 1; Figure 3 is a section on line III—III of Figure 1;

Figures 4 through 8 are detailed sections of various forms of front edge sealing constructions;

30 Figure 9 is a detailed section of the preferred form of front edge construction for the seal;

Figure 10 is a view similar to Figure 9, except showing a modified form fastening the panel to the structural members forming the front and rear frame members; and,

35 Figure 11 is a detailed section of a modified form of construction for the top frame and seal.

In the present construction, the door comprises a framework including front, rear, top and bottom commercial shapes rigidly secured together, in 40 any conventional manner, to form a rigid continuous rectangular frame. The front frame member comprises a main body portion 2 and a forwardly extending flange portion 3 and a rearwardly extending flange portion 4 integral therewith and at right angles to the main body portion 2. The rearwardly extending flange portion 4 has connected thereto, in any conventional manner, the metallic sheet or sheets, as may be desired, such sheet or sheets 13 forming the wall or 45 panel of the door. The main body portion 2 of each of the commercial shapes forming the framework for the door construction is deformed at right angles to its normal plane to provide a flange portion 5, as clearly illustrated in the respective figures, which flange portion is spaced from and extends in parallel relation to the forwardly extending flange 3. The edges of the sheet 55 13 or separate panels, as the case may be, are bent laterally from the main plane of the panel 60 in order to be secured, in any conventional man-

ner, to the main body portion 2, or if desired, secured to the flange 5 as illustrated in Figures 1 to 4, inclusive. As illustrated in Figure 10, the sheet or sheets forming the door panel, extends flush with the rear flange 4 of the front frame member and the forwardly extending flange 3a of the rear member, and abuts the main body portion 2 of each front and rear frame member. If desired, the sheet or sheets may be welded to the main body portion 2, or to both the main body portion and the flanges 3 and 4.

Secured to a door post 6 is a front stop member 7 provided with an outwardly extending flange member 8 which, in Figure 3, is shown as being bent substantially at right angles to the plane of the member 8 and thence outwardly to form a portion 9 which is in substantial parallelism with the main body portion 2 of the commercial shape, but spaced therefrom. The right-angled portion 10 of said flange 8 forms, with said flange, an abutment or stop for the forwardly projecting flange 3 of the front frame member, while the outwardly extending portion 9, combines with the main body portion 2, to form a pocket 15 adapted to collect sparks, cinders and any other extraneous matter that might attempt to seep into the interior of the car.

As shown in Figure 4, the member 12, which is secured to said flange 8, in any desired manner, may have a substantially U-shaped construction to abut the inner surfaces of flange 3 and the main body portion 2. There is formed a pocket or channelway 15 in communication with the top and bottom of the door. An opening 11 is provided on one flange of said member 12 to provide ready access for the fastening of said member 12 to the flange 8.

In Figure 5, the flange 8 has secured thereto, in any conventional manner, a member 12 which is deformed to fit snugly within the channelway formed between the flanges 3 and 5. This member 12 is provided with a portion 14 which extends beyond the extremities of the flange 5 and abuts the lower portion of the flange 8, thereby providing a channelway or pocket extending vertically throughout the entire length of the door opening, said pocket 15 communicating with the channelway 15 at the top of the door and with the open space at the bottom.

In Figures 6, the flange 8 has an integrally formed right-angled portion 10 and an outwardly extending flange portion 9, rebent to form a substantially U-shaped cross section adapted to extend into the channelway formed by the flanges 3 and 5, so as to form a spark-seal.

In Figures 7, 9 and 10, the member 12 may have substantially an L-shaped cross section which, in Figure 7 is secured to the inner surface of the flange 8 and abuts the forwardly extending flange 5 and the main body portion 2. In Figures 9 and

10, the L-shaped member is so positioned and arranged as to engage the inner surface of the forwardly extending flange 3 and the main body portion 2. In each instance, there is likewise provided a pocket 15 to receive sparks, cinders or other extraneous matter which may pass downwardly through the channelway to the open space at the bottom of the door.

In Figure 8, the member 12 is substantially U-shaped in cross section and being secured, in any conventional manner, to flange 3, engages the inner surfaces of the flanges 3 and 5 and main body portion 2 and forms a spark-seal pocket 15 as described in the other views.

15 The rear commercial shape, as illustrated in Figure 3, has its main body portion 2^a bent at right angles to its normal plane and extending rearwardly therefrom to provide the flange 5^a. The rearwardly extending flange 5^a, of the rear commercial shape, is deformed at right angles and extends inwardly from the main plane of the door and is in substantial parallelism with the main body portion 2^a. Secured thereto, in any conventional manner, is a member 16 provided with a laterally extending flange 17 which is adapted to form a wedged contact with the flange 18 of the rear stop member 19 secured to the rear door post 20. Therefore, there is provided a sealing pocket adapted to receive cinders or the like that might seep past the member 16.

30 The top commercial shape, as illustrated in Figure 2, has the flange member 5^b bent at right angles to the main body portion 2^b, so that it is in substantial parallelism with the flange 3^b, thereby forming across the top of the door, a substantially trough-shaped channelway. Secured to the side plate 21, in any conventional manner, is a member 22 inclined outwardly and downwardly and terminating in a flange 23 in substantial parallel relation to the flange 5. Secured to the member 22, in any conventional manner, is a plate 24 having a downwardly extending flange 25 in parallel relation to the flange 3^b and positioned between said flange 3^b and the depending flange portion of the side plate 21. Under such a construction, there is provided a spark-seal for the top of the door, which requires sparks, cinders, or other extraneous matter to pass upwardly through the space between the flange 23 and flange 5^b into the trough-like passageway where it is trapped rather than continue upwardly and then downwardly through the space between the flanges 3^b and 25.

35 In the modified form illustrated in Figure 11, the side plate 21 has secured thereto, in any conventional manner, the commercial shape 24' which is provided with a flange 25' extending over the flange 3^b. A cover plate 22' is secured, in any conventional manner, to the flange 25' and extends outwardly and downwardly therefrom so as to form a flange 23' positioned to overlie the flange 5^b of the door frame. Such a construction forms, as in Figure 2, a pocket or channelway 15 in communication with the pocket 60 provided at the front edge of the door and with the open rear end thereof.

The bottom commercial shape, as illustrated in Figure 2 includes the main body portion 2^c bent downwardly at right angles thereto to provide the flange 5^c in spaced parallel relation to the flange 4^c. The flange 3^c is secured, in any conventional manner, to the panel of the door. The flange 4^c has its end portion 26 bent inwardly of the main plane of the door, with said portion

26 being substantially parallel to the main body portion 2^c and adapted to snugly rest upon the flange 27 of the threshold plate support 28 when the door is in closed position. The threshold plate 29 is provided with a downwardly extending flange 30. When the door is in closed position, as shown in Figure 2, it becomes apparent that there is produced a spark-seal for the bottom of the door, and should any sparks or cinders seep past the seal between flanges 26 and 27, it would then be trapped within the pocket 31.

Under such a construction as hereinabove described, there is provided a car door having spark-sealing means on all four sides. The spark-seal pocket formed at the front edge of the door extends vertically throughout the entire length of said door and communicates, at the top, with the trough-shaped channelway while the lower end of the pocket is open, which permits sparks or other extraneous matter to drop down through the bottom of the door into open space. The upper pocket or channelway is also in communication with the open rear edge of the door so that extraneous matter accumulating therein can empty into the open space formed at the rear door edge. The bottom spark-seal pocket precludes sparks or extraneous matter from entering into the interior of the car due to the flange 30 deflecting any sparks which might seep past the contact point between flanges 26 and 27 into pocket 31.

30 While I have shown and described specific embodiments of the present invention, it will be seen that I do not wish to be limited exactly thereto, since various modifications may be made without departing from the scope of the invention as defined by the following claims.

I claim:

1. In combination with a front stop member, a railway car door including a plurality of commercial shapes rigidly connected together to provide a continuous frame structure and including a commercial shape T-shape having its leg bent parallel to one of its flanges to provide extending spaced flanges forming a spark-seal pocket.

2. A door for a railway car comprising front, rear, top and bottom commercial shapes rigidly connected together to provide a continuous frame structure, a panel secured to said frame structure, each of said commercial shapes comprising a main body portion extending outwardly from the plane of the door opening, spaced flanges formed integral with said main body portion and at right angles thereto so as to extend outwardly and door frame parts adapted to form with said flanges a spark and weather-seal pocket around the door.

3. A railway car door comprising commercial shapes rigidly connected together to provide a continuous frame structure, a panel connected to said frame structure, the front commercial shape comprising a main body portion extending outwardly from the plane of the door opening, a flange integral with said main body portion and at right angles thereto, a portion of said main body portion bent at right angles thereto and in spaced parallel relation to said first mentioned flange, a front stop member for said door, said stop including an outwardly extending flange combining with the flanges of said front commercial shape to provide a spark-seal pocket extending throughout the entire length of said door structure.

FINN OYEN.
